UNITED STATES PATENT OFFICE.

JEREMIAH H. ZEIDERS AND LEWIS S. ZEIDERS, OF HARRISBURG, PENNSYLVANIA.

BED-SPRING.

No. 909,504.

Specification of Letters Patent.

Patented Jan. 12, 1909.

Application filed February 18, 1908. Serial No. 416,543.

To all whom it may concern:

Be it known that we, JEREMIAH H. ZEIDERS and LEWIS S. ZEIDERS, citizens of the United States, residing at Harrisburg, 5 in the county of Dauphin and State of Pennsylvania, have invented certain new and useful Improvements in Bed-Springs, of which the following is a specification, reference being had to the accompanying drawings.

10 Our invention relates to improvements in bed springs and more particularly those especially designed for the use of invalids and having adjustable head sections.

The object of the invention is to provide 15 a device of this character which will be simple, strong, durable, and comparatively inexpensive in construction and which may be readily adjusted so that the head section may be supported at any desired inclination.

20 With the above and other objects in view, the invention consists of the novel features of construction, and the combination and arrangements of parts hereinafter fully described and claimed, and illustrated in the 25 accompanying drawings, in which—

Figure 1 is a top plan view of our improved bed spring; Fig. 2 is a vertical longitudinal section taken on the plane indicated by the line 2—2 in Fig. 1; Fig. 3 is a 30 vertical transverse section; Fig. 4 is a detail section taken on the plane indicated by the line 4—4 in Fig. 1 and showing one of the fasteners for retaining the adjustable or spring frame upon the bedstead or stationary frame; Fig. 5 is a perspective view of one of 35 said fasteners; Fig. 6 is a perspective view of the rock shaft and the two ratchet members or plates; Fig. 7 is a detail section taken on the plane indicated by the line 7—7 40 in Fig. 1; and Fig. 8 is a perspective view of the cross-bar for the lace.

In the drawings, we have shown a bed- 45 stead or frame 1, of ordinary construction, having head and foot pieces 2, 3 united by angle metal side bars or rails 4.

50 5 denotes a mattress supporting frame which is removably mounted on the bedstead or stationary frame 1 and which is covered by the usual elastic woven wire fabric 6, or any other suitable elastic or flexible covering. The frame 5 consists of a main or foot section 7 and a vertical

55 swinging head section 8, which latter is united to the frame by strap hinges 9 or any other suitable pivotal connections. The section 7 of the frame 5 is preferably composed of two side bars 10 united by a cross or end bar 11 to which latter one end of the wire fabric covering 6 is secured by a clamping strip 12 in the usual manner. The head 60 section 8 is similarly composed of side bars 13 united at their inner ends by the hinges 9 and the bars 10 and connected at their outer ends by an end bar 14 to which latter the other end of the covering 6 is secured 65 by a clamping strip 15. The side bars 10, 13 are adapted to enter between the side rails 4 of the bedstead and the projecting ends of the bars 11, 14 rest upon the latter to support the frame 5 when its two sections 70 are extended in longitudinal alinement. The head section 8 is adapted to swing upwardly to an angular position and, when in such position, the inner part of the section 7 is supported from the side rails 4 by projecting supports 16 preferably in the form 75 of angle brackets 16 secured upon the outer faces of the bars 10 adjacent to their inner ends, as clearly shown in Figs. 2 and 3. The swinging head section 8 is adapted to 80 be locked in any of its inclined or angular positions by a ratchet locking device consisting of two swinging ratchet plates or members 17 fixed upon the ends of a rock shaft arranged transversely beneath the 85 inner ends of the bars 10 and mounted for rotation in suitable bearings 18 secured upon the bottom faces of said bars 10. The intermediate or central portion of the rock shaft is bent into substantially U-form to 90 form a crank handle or loop 19 by means of which the ratchets 17 may be conveniently operated. Said ratchets 17 are in the form 95 of metal plates or strips having their free ends formed with ratchet recesses or notches 20 and projecting through substantially 100 U-shaped guide loops 21 arranged upon the inner ends of the bars 13 of the head section. The lower portions 22 of the guides 21 are adapted to enter the ratchet recesses 100 20 and thus serve as fixed pawls or keepers for the ratchet members.

It will be seen that when the crank loop or handle 19 is swung towards the head of

the bed, the ratchet members 17 will be lifted in the combined guide loops and keepers 21 to release the head section 8 which may then be swung either upwardly 5 or downwardly, and that when the ratchet notches 20 in the members 17 drop over the lower portions 22 of the keepers the head section will be secured in adjusted position.

When the covering 6 is in the form of 10 elastic woven wire fabric it is stretched tightly over the frame 5 when the two sections are in longitudinal alinement with each other so that when the ratchet device is operated to unlock the head section the 15 elasticity of the spring covering 6 will elevate the head section 8. To support the portion of the covering 6 above the section 7 of the frame 5 in a substantially horizontal position when the head section is 20 elevated, we provide a connection between said covering and the inner end of the head section. This connection is preferably in the form of a flexible strip 23 of leather or the like laced back and forth between the 25 covering 6 and the perforated cross bar 24 arranged beneath the inner portion of the head section 8 and having its ends secured to the side bars 13 of the latter.

For the purpose of preventing the section 30 7 of the frame 5 from tilting when the head section 8 is in an adjusted angular position, we provide suitable fasteners, preferably in the form of turn buttons 25 pivoted, at 26, upon the projecting ends of the bars 11 35 and adapted to swing under the inwardly projecting flanges of the angular side rails 4 of the bedstead, as clearly shown in Fig. 4. If desired, we may provide similar catches or fastenings 27 upon the projecting 40 ends of the bar 14 to secure the head section 8 in a horizontal position on the bedstead.

From the foregoing it will be seen that our invention is simple, and practical in construction so that it may be produced at a 45 comparatively small cost and will be strong and durable in use. It is also exceedingly convenient in operation, and may be adjusted by the occupant of the bed.

While we have shown our improved bed 50 spring mounted in a bedstead of ordinary construction it will be understood that it may be embodied in a bed, couch, or similar piece of furniture of any form and construction. It will also be understood that various 55 changes in the form, proportion, and minor details of construction may be resorted to without departing from the spirit or sacrificing any of the advantages of the invention.

Having thus described our invention what we claim is:

1. The combination of an adjustable frame having hingedly connected foot and head sections, a covering for the frame at-

tached to the outer ends of its sections, a 65 cross bar arranged beneath the inner portion of the head section and having its ends attached to the sides thereof, the intermediate portion of said cross bar being offset and formed with a longitudinal series of 70 apertures, a lacing strap laced back and forth through said covering and the apertures in the offset portion of the cross bar and means for securing the head section in an adjusted position. 75

2. The combination of an adjustable frame having hingedly connected foot and head sections, each consisting of side bars united by end bars, a covering for the frame attached at its ends to the end bars of the 80 sections, a connection between the intermediate portion of the covering and the inner end of one of the sections, bearings upon the side bars of the foot section, a transverse shaft journaled in said bearings, the guide 85 and keeper loops 21 upon the side faces of the side bars of the head section, the ratchet plates 17 fixed to said shaft and adapted to project through said loops, the bottom edges of said plates being formed with a series 90 of ratchet recesses to drop by gravity into engagement with the lower portions of said loops to lock the head section in an adjusted angular position and a crank handle for actuating said shaft. 95

3. The combination of an adjustable frame having hingedly connected foot and head sections, each consisting of side bars united by end bars, a covering for the frame attached at its ends to the end bars of the 100 sections, a connection between the intermediate portion of the covering and the inner end of one of the sections, bearings upon the side bars of the foot section, a transverse shaft journaled in said bearings and having 105 its intermediate portion offset to provide the crank handle 19, the keeper loops 21 fixed to the side faces of the side bars of the head section and the ratchet plates 17 fixed to the ends of the shaft and arranged in said loops, 110 substantially as and for the purpose set forth.

4. The combination of a stationary rectangular frame, an adjustable frame having hingedly connected foot and head sections, 115 each section consisting of side bars united by end bars, a covering upon the adjustable frame having its ends attached to the end bars of its sections, a connection between the intermediate portion of the covering and the inner end of one of said sections, means for adjusting the head section angularly 120 with respect to the foot section, the angle brackets 16 on the side bars of the foot section to rest upon the top of the stationary 125 frame and support the inner end of the foot section, the outer end of the latter being supported by the engagement of the projecting

ends of its end bar with the top of the stationary frame and the turn buttons 25 at the outer end of the foot section to hold the latter down upon the stationary frame and prevent it from tilting when the head section is elevated.

5 In testimony whereof we hereunto affix

our signatures in the presence of two witnesses.
